UNITED STATES PATENT OFFICE.

GEORGE W. VOIGT, OF CHICAGO, ILLINOIS, ASSIGNOR TO JOHN T. GIBLIN, OF CHICAGO, ILLINOIS.

MECHANISM FOR OPERATING CAR DOORS AND STEPS.

1,043,483.

Specification of Letters Patent.

Patented Nov. 5, 1912.

Application filed February 1, 1911. Serial No. 605,985.

To all whom it may concern:

Be it known that I, GEORGE W. VOIGT, a citizen of the United States, residing at Chicago, in the county of Cook and State of Illinois, have invented certain new and useful Improvements in Mechanism for Operating Car Doors and Steps, of which the following is a specification.

This invention relates to mechanism for opening and closing the doors of street railway cars and for moving into and out of operative position a step adjacent to said door, the primary object of the invention being to produce means for this purpose which may be conveniently operated by the motorman, and is simple, efficient and strong so that it will be capable of withstanding the rough usage which in practice it is apt to receive.

20 Further objects and advantages of the invention will be understood from the detailed description hereinafter set forth.

In the accompanying drawings, Figure 1 is a view showing in dotted outline a vertical longitudinal section through a street railway car platform, the door appearing in inside elevation, said view further illustrating inoperative association with the platform a mechanism embodying my invention for opening and closing the door and for moving the step into and out of operative position, the step also appearing in inside or rear side elevation. In this view the door is shown closed and the step in its inoperative position. Fig. 2 is a fragmental plan view of the platform and operating mechanism, the platform being indicated in dotted outline. Figs. 3 and 4 are fragmental transverse vertical detail sectional views in the plane of line 3—3 of Fig. 2, showing the step in its inoperative and its operative positions respectively. Figs. 5, 6 and 7 are fragmental detail views of the means for connecting the operating lever to the door. Fig. 8 is a fragmental detail sectional view illustrating the stop means for the operating staff, the view being taken in the plane of line 8—8 of Fig. 1.

The portion of the mechanism herein shown for opening and closing the door is substantially similar to that shown in my prior Patent No. 965,770 issued July 26, 1910, but it should be understood that the means for operating the step may be con-

nected with a door operating mechanism of 55 different construction.

In the drawings, A indicates a street railway car platform having a door B movable thereon. In the form herein shown, the door operating mechanism comprises a lever 1, pivoted at its lower end at 2 to a suitable part of the car platform, the upper end of said lever having a slidable connection with the door B so that when said lever is swung, the door will be opened and closed. The connection herein shown between the lever 1 and the door is somewhat different from that shown in my said patent, the present connection comprising a rounded member 3 secured to the rear edge of the door, a rod 4 spaced from the member 3 and having its ends fixed to brackets 5 which are secured to the edge of the door, and a grooved stud 6 secured to the upper end of the lever 1 and adapted to travel between the member 3 and the rod 4 in the swinging movements of the lever 1.

In order to cushion the closing movement of the door so as to prevent injury to a person's hand or clothing which may happen to be in the path of movement of the door, and also for a further purpose to be later described, I provide a coiled spring 7 surrounding the rod 4 at its lower end and a block 8 slidable on said rod, the stud 6 engaging said block in its downward movement and compressing the spring 7 as the door is closed.

The means for swinging the lever 1 to open and close the door B may comprise a rock shaft 9 mounted in bearings 10, carried by the platform A, the shaft being positioned at some distance below the pivot point 2 of the lever 1. Fixed to the shaft 9 is an arm 11 which carries at its upper end a block 12 slidable in a slot 13 in the lever 1. The shaft 9 may be rocked by means of the vertical staff 14 mounted in suitable bearings on the platform A, said staff having at its upper end a handle or crank 15 and at 90 its lower end a crank arm 16 which is connected by means of a link 17 with an arm 18 upon the rock shaft 9. The staff 14 is rotated clockwise when the door is being closed. The arm 16 at the lower end of the staff 14 is arranged to throw over center when the door is closed, as shown in Fig. 2, so as to lock said door in its closed position.

Any common or suitable means such as that shown in Fig. 8 may be provided to prevent the staff 14 from rotating farther in a clockwise direction than the position shown in Fig. 2. In the present instance, said stop means consists of a collar 31 fixed by means of a set screw 33 on the staff 14 and having a stop 29 thereon which strikes against a lug 30 on a bracket 32, which is attached to the car frame and in which the upper end of the staff 14 turns.

When the parts are in the position indicated in Figs. 1 and 2 the door is fully closed and the spring 7 is compressed between the roller 6 and the lower bracket 5. Said spring therefore tends to raise said roller and open the door, thus swinging the lever 1 rearwardly and moving link 17 endwise rearwardly. It will therefore be seen that the action of the spring 7 tends to hold crank arm 16 and link 17 in their "over center" position, as indicated in Fig. 2.

The step 19 is movably mounted in any suitable way, being pivoted in the present instance to brackets 20 fixed to the platform A so as to be tilttable into a vertical or inoperative position, as shown in Fig. 3, or into the horizontal or operative position, as shown in Fig. 4. At the rear edge of the step 19 is an extension 21 which may be longer than the step 19, as shown in Fig. 1, said extension serving, when the step is in its inoperative position, as a guard to prevent persons or objects from being thrown beneath the wheels of the car, in a manner well understood. The step 19 is arranged to be swung by means of a bell-crank lever 22 pivoted at its angle to any suitable part such as a bar 23 secured to the under side of the platform, one arm of said bell-crank being connected by means of a link 24 with an ear 25 on the rear edge of the step 19 and the other arm of said lever being connected by means of a link 26 with an arm 27 upon the rock shaft 9. The outer end of the link 24 extends through a slot 28 in the extension 21 upon the step 19. The relation of the parts is such that when the door is opened and closed, the step will be correspondingly lowered or raised. The step 19 and the guard or extension 21 lie at opposite sides of their pivot line and substantially counterbalance each other so that the action of the step mechanism is even and smooth.

In operation, when the car is stopped to let off passengers, the motorman swings the handle 15 to open the door 13 and to lower the step 19 so that the passengers may descend from the car.

I claim as my invention:

1. The combination with a car platform, a door movable thereon, and a pivotally mounted step adjacent to said door, of means for moving said door comprising a vertical staff having a handle thereon, a

rock shaft, an operative connection between said staff and said rock shaft, a bell-crank lever, a connection between one arm of said bell-crank lever and said rock shaft, and a connection between the other arm of said lever and said step. 70

2. The combination with a car platform, a door movable thereon, and a step pivotally attached to the platform beneath said door, of mechanism for operating said door and said step comprising a rock shaft, a lever pivoted at one end and connected at its other end with said door, an arm on said rock shaft engaging said lever, a vertical staff having a handle at its upper end, an arm on the lower end of said staff, a second arm on said rock shaft, a link connecting the two last mentioned arms, a bell-crank lever pivoted at its angle upon said platform, a link connecting one arm of said bell-crank lever 85 with said step for swinging the latter, a third arm on said rock shaft and a link connecting the other arm of said bell-crank lever with said third arm. 80

3. The combination with a car platform 90 having a door and a step movably mounted thereon, of means for operating said door and step comprising a vertical staff mounted in the platform to oscillate on its main axis, an operating handle on the upper end of 95 said staff and a crank arm on its lower end, a horizontal rock shaft mounted beneath the floor of said platform and extending transversely of the car, an arm on said rock shaft, a link connecting said arm with the crank arm on said operating staff, an arm on said rock shaft operatively connected with said door, and an arm on said rock shaft having a link connection with said step. 100

4. The combination with a car platform 105 having a door movably mounted thereon and having a step pivotally attached thereto beneath said door, of a staff mounted on the platform, means connecting the lower end of said staff with said door for opening and closing the latter, a connection between said door moving means and said step for pivotally moving the latter into and out of operative position, and an elongated board-like extension at the rear edge of said step serving as a guard when in a vertical position and acting as a means for counterbalancing said step whereby to facilitate operation of the mechanism. 110 115

5. The combination with a car platform 120 having a door slidably mounted in the forward portion thereof and having a step pivotally mounted thereon beneath said door, of mechanism for simultaneously operating said door and said step comprising an operating staff mounted on the platform, a horizontal rock shaft extending transversely of the car beneath the floor of said platform and adjacent the rear end thereof, a connection between the lower end of said staff and 125 130

said rock shaft for rocking the latter, an arm on said rock shaft having an operative connection with the rear edge of said door, a lever pivoted to the platform adjacent said 5 step, a transversely extending link connecting said lever with said step, a second arm on said rock shaft, and a link connected to said second arm, the last mentioned link ex-

tending forwardly and being connected to said lever.

In testimony whereof I affix my signature in presence of two witnesses.

GEORGE W. VOIGT.
